ATTORNEY

UNITED STATES PATENT OFFICE

WILLIAM GREEN, OF BROOKLYN, NEW YORK

WINDOW GUARD

Application filed June 23, 1928. Serial No. 287,741.

This invention relates to window guards. An object of the invention is to provide a practical device of the character described in which the guard body comprises a supporting structure for the adjustable parts of the device, and may be centered with respect to the device when used with windows of various sizes.

A further object of the invention is to provide a device of the character described, which shall be simple in construction, form a neat and attractive article which is cheap to manufacture and practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims:—

Fig. 1 is a front elevational view of a window guard embodying the invention;

Fig. 2 is a cross-sectional view taken on line 2—2 of Fig. 1;

Fig. 3 is a cross-section view taken on line 3—3 of Fig. 1; and

Fig. 4 is a front elevational view showing the device fitted in a window.

Referring in detail to the drawing, 10 designates the window guard which is here seen to comprise extensible sections A and B and a guard body C.

The section A comprises an end frame member 11 of angular cross-section and a number of similar horizontal tubular members 12 attached to said angular member. As here illustrated, three such members 12 are provided, the top tube being designated *a*, the bottom tube as *b* and the middle tube as *c*. Obviously the number of such horizontal tubes may be increased or decreased as desired. To secure said tubes 12 to the angle member 11 one end 13 of each tube 12 is flattened to bring the walls of said tube together at said end. Said flattened portions 13 may be secured to one arm 11^a of

member 11 as by rivets 14, and the outer end portions 15 of said flattened portion 13 may be bent at right angles and likewise riveted as at 16 to arm 11^b of said member 11.

Section B comprises an end member 17 of angular cross-section, similar to member 11, and bars 18 secured to said member 17, bar 18 being provided for each tube. Said bars are secured to arms 17^a, 17^b of member 17 by rivets 19 and 20 respectively, aligned with rivets 14 secured to tubes 12 and 16. The tubes 12 are suitably shaped to slidably receive the bars 18, as shown in Fig. 3.

It will now be understood that the sections A and B may be pulled apart or pushed together to adjust the width of the device 10 to fit window openings of various dimensions. The end members 11 and 17 may be provided with suitable openings 32 in arms 11^b and 17^b respectively for receiving screws or the like for securing the device to the side frames 21, 22 of a window 24.

The guard body C may be constructed of strong wire, bent and twisted to form an X-shaped member 25 mounted on the horizontal telescoping members 12, 18. The outer ends of said member 25 are preferably formed with looped extensions 26 loosely receiving tubular members *a* and *b*. The mid-portion of said member 25 is likewise looped as at 27 to receive the middle tubular member *c*. The outer ends of member 25 may be connected by vertical double wire bracing members 29, which may also be formed with loop portions 30 surrounding the tubular member *c*. Said vertical members 29 may be bent to form substantially elliptical shaped loop portions 31 between the members *a* and *b*, and between the members *b* and *c*. The loops 26, 27, 30 are shaped to permit the guard body C to be shifted on the horizontal members 12. Thus said guard may be centered on the sections A, B when said sections are adjusted to fit windows of different widths. Said guard constitutes a strong frame for the telescoping members, provides ample guarding surface to prevent infants from falling thru the window and yet does not obstruct light from the window.

The wire comprising the frame C may be bent and twisted in any manner desired to form the portions designated. Several pieces of wire may be used, the ends of said wires being soldered to portions of adjacent wire. Where the wire is twisted several times, as above and below loop 27, the turns may be soldered to each other to form a rigid structure.

10 The sections A and B may be entirely separated for shifting or replacement purposes. When separated from section B, the tubular members 12 of section A may be threaded thru the loops 26, 27, 30. The bars 18 of section B may then be slid into said tubular members 12. The window guard may then be adjusted to the required width and secured to the window frames 21, 22, and frame C may then be slid to the right or left as necessary to center said frame to give the device a balanced and pleasing effect and also to avoid large unguarded areas in the window guard.

25 It will thus be seen that there is provided a device in which the several objects of this invention are achieved, and which is well adapted to meet the conditions of practical use.

30 As various possible embodiments might be made of the above invention, and as various changes might be made in the embodiment set forth, it is to be understood that all matter herein set forth or shown in the accompanying drawing is to be interpreted as illustrative and not in a limiting sense.

35 Having thus described my invention, I claim as new and desire to secure by Letters Patent:

1. A window guard comprising extensible sections, and a bent wire frame member mounted for sliding movement on said sections.
2. A window guard comprising interengaging members, and a guard body having looped portions slidably receiving said members.
3. A window guard comprising extensible sections having interengaging members and an X-shaped frame having looped extensions at the outer ends thereof, the central portions of said frame having a loop portion, said loop receiving said interengaging members for sliding movement.
4. A window guard comprising a pair of extensible sections having interengaging telescoped portions and a frame member slidably mounted on said portions.

50 In testimony whereof I affix my signature.

60 WILLIAM GREEN.
